UNITED STATES PATENT OFFICE.

JAMES H. McDOWELL, OF BROOKLYN, NEW YORK.

FUSIBLE LINK.

1,317,629.

Specification of Letters Patent. Patented Sept. 30, 1919.

Application filed November 13, 1917. Serial No. 201,729.

To all whom it may concern:

Be it known that I, JAMES H. McDOWELL, a citizen of the United States, residing in the city of New York, borough of Brooklyn, county of Kings, and State of New York, have invented a certain new and useful Fusible Link, of which the following is a specification.

This invention is a fusible link adapted for use with automatic sprinklers, fireproof windows, and in any other environment where fusible links are generally employed.

Fusible links have long been known and, in almost every case, embody two or more opposed tension members with an intermediate key-piece. In the majority of links heretofore employed two tension members are used, each of which is provided with a tapered pocket formed in the inner face of each

20 of said tension members and so positioned therein that, when the complementary tension members are placed in lapped relation, the two pockets will together form a chamber which houses a key-piece having flat 25 sides which abut the ends of the chamber. The parts are held together by fusible solder. The key-piece, which is in the nature of a strut, lies within the chamber in a position diagonally through the medial line of the

30 length, as viewed from the longitudinal edge thereof, and this position of the parts is maintained until the fusible solder is melted through the currents of local excessive heat, at which time the solder will no longer hold 35 the parts of the tension members in face abutting relation but will allow them to separate under a pull in opposite directions on the respective tension members. In order that the links may move relative to one an-

40 other longitudinally, it is generally necessary that the key-piece be tilted while its opposite ends remain either seated in the base of the depressions or in contact with the edges formed by the intersection of the de- 45 pressions with the inner faces of the tension members. This tilting of the key-piece forces the tension members apart, disrupting the fusible solder, and separating the parts of the link.

50 In links of the character described, which is that quite commonly used, a relatively wide separation between the tension members is required before the parts of the link are entirely disassembled. During this operation the opposite edges of the strut re- 55 main in contact with the same points of

the tension members. This is due to the fact that the operation of the link is dependent upon the tilting of a strut to a position substantially at right angles to the 60 medial line of the link or its opposite ends, or maintained in substantial fixed position relative to the respective tension members. This wide separation of the parts is objectionable, particularly if the device is used 65 to control a sprinkler so that, when these devices have been heretofore employed with sprinklers, the struts have been made exceedingly small and did not possess the great strength which was otherwise obtainable in 70 this form of link. For the reasons given, other forms of fusible link have generally been used in sprinkler control. For example, those forms of link wherein a transversely extending, cylindrical strut or a 75 ball is employed as a key-piece. Such links, while requiring but a very small separation of the parts, do not possess the strength of the link wherein the relatively flat surfaces of the key-piece come into engagement with 80 the relatively flat surfaces of the tension members as is the case with the strut links referred to.

With the foregoing considerations in mind, the object of the present invention is to combine in a single link all the advantages of both forms of link referred to without including their disadvantages; that is to say, to provide a strong and reliable link which will be quick in opening and yet not require great separation between the tension members before becoming entirely disrupted. 85

These features are obtained in the link of this invention by so constructing the key-piece and tension members that, during the 90 disrupting action of the link, there are numerous forces at work. For example, the pressure of the tension members upon the relatively flat surfaces formed in the key-piece on diametrically opposite sides of the axis 100 of rotation thereof causes a rotation of the link on its transverse axis, and, by the action of such rotation, the tension members are positively forced apart and separated by the edges of said key-piece which engage 105 with the inner faces of the tension members. There are thus certain forces operating to rotate the key-piece into a position to allow the tension members to slip by one another by longitudinal movement and other forces 110 acting to separate or force the tension members apart. The tension members have no

bearing on any particular points or portions of the key-piece, as heretofore, but the points of engagement are constantly varying, thus producing a very active structure 5 when operated, which results in a quick opening link and, at the same time, a very strong link in the absence of disrupting heat.

Features of the invention, other than 10 those specified, will be apparent from the hereinafter detailed description, read in conjunction with the accompanying drawings.

In the accompanying drawings, I have 15 illustrated different practical embodiments of the present invention, but the constructions shown therein are to be understood as illustrative, only, and not as defining the limits of the present invention.

Figure 1 is a perspective view of the preferred form of link of this invention, said link embodying a transversely extending key-piece.

Fig. 2 is a modified form of link embodying the same invention but having a key-piece in the form of a globular section.

Fig. 3 is a central, longitudinal section through the link of Fig. 1 showing the parts in assembled relation.

Fig. 4 is a similar view of the structure 30 of Fig. 2.

Fig. 5 is a greatly enlarged view of the structure shown in Figs. 2 and 4, showing a portion of the link at the time of opening or disrupting.

Fig. 6 is a detail perspective of the key-piece shown in Figs. 1 and 3, and

Fig. 7 is a detail side elevation of the key-piece of Figs. 2 and 4.

In the form of the invention illustrated in 40 Figs. 1, 3 and 6 the same embodies two tension members A and A'. Each tension member is provided at its opposite end with apertures a and a', respectively, through which a cable or hook may be passed for including the fusible link in a chain or associating it with any other form of mechanism which it is to control. The tension members A A' may be of any desired shape which may vary in accordance with the environment in which the link is adapted to be 45 employed. The shape is of no consequence, the invention being directed, more particularly, to the formation of the key-piece B of the link and the pockets or depressions 50 formed in the tension members for the reception of certain portions of said key-piece.

The tension members A and A' are adapted to be placed in lapped relation, as shown in Figs. 1 and 3, with the key-piece B, shown 60 in detail in Fig. 6, positioned between said members and extending transversely thereof. The members are spaced very closely together and united by fusible solder b, each of said members being provided, in its inner 65 face, with a transverse depression or pocket

d, in tension member A, and d' in tension member A', and the key-piece B extends into said depressions and is housed thereby.

The key-piece, instead of being rectangular in cross section as has generally heretofore been the case, is rabbeted or grooved on its opposite faces to provide substantially parallel faces e e', and substantially parallel faces f f'. In order that the relationship of these faces may be clearly understood the medial plane of the link is shown in dotted lines in certain figures and is designated c, while a plane c' is shown which is perpendicular to the plane c and passes through the center of the key-piece. The key-piece is positioned intermediate the members A A' in transverse position, and the depressions d and d' are shaped in conformity with the contour of said key-piece, as shown in Fig. 1. It will be noted that, 85 when in this position, the face c abuts the inner face of member A, while face e' abuts the inner face of member A' and, as the faces of said members are spaced apart by the fusible solder b, the faces e and e' are 90 accordingly spaced a short distance from each side of the medial plane c, as shown best in Fig. 6, so that they are, in effect, offset a short distance though lying in planes parallel to one another. This formation of 95 the key-piece facilitates the assembling of the link and assures the proper distance between the tension members.

The faces f and f', which are adapted to abut with faces d² and d³ of the depressions 100 d and d', respectively, are preferably parallel and preferably make an angle greater than ninety degrees with the faces e and e' so that said faces f and f' are sloping with respect to the plane c' although, if desired, 105 said faces f and f' may coincide with the plane c'. The advantage of having the faces e and e' off-set and the faces f and f' sloping is that the link cannot act upon "dead centers" as there will always be a 110 tendency, if the solder is released, to roll the key-piece about the line of intersection of the planes c and c'. Thus, while the faces e and e' may be in alignment, it is preferable that they be off-set, as described, and 115 the faces f and f' sloping.

In the construction of Figs. 1 and 3 the key-piece B is shown as extending the entire width of the link but, in practice, it may be of lesser length and positioned in 120 pockets intermediate the edges of the link so that said pockets do not extend to said edges. The key-piece B may thus be made in the shape shown in cross section in Fig. 6 but of lesser length or, such modified form may partake of the configuration shown in Figs. 2, 4 and 7 where the key-piece is shown as of spherical contour. In the modified form shown in said first mentioned figures a sphere B' is provided with 125 130

the cut faces e and e' and the other cut faces f and f' corresponding to the similarly referred to faces of the key-piece, shown in Fig. 6.

5 The mode of operation of both forms of the invention described is practically the same and, in order that it may be clearly understood, attention is directed to Fig. 5 which shows the link in the operation of 10 disrupting. The construction of Figs. 2, 4, and 7 is shown in Fig. 5 but it will be understood that the same *modus operandi* applies equally well to the preferred form 15 first described. To obviate prolixity, the same reference numerals as applied to the construction of Figs. 1, 3 and 6 will be applied to Fig. 5 with the exception that the sphere will be designated B' as in Figs. 20 4 and 7. In this connection it will be apparent from the drawings that the tension members of the modified embodiment are formed the same as the tension members of Fig. 1 with the exception that the depressions in which the sphere is seated are, of 25 course, shaped to conform with the contour of said sphere after the same manner as the depressions d and d' are shaped to conform to the key-piece shown in Fig. 6. It will be assumed, with reference to Fig. 5, that 30 the link included in a chain or other tension element, as is generally the case, is impelled by a force upon the tension member A in the direction of the double arrow shown at its upper end, while a similar force 35 is exerted upon the member A' in the direction of the double arrows shown at its lower end. These forces tend to slide the members longitudinally of one another, respectively, in the direction of the double 40 arrows.

As long as the solder unites the parts they partake of the position shown in Fig. 4 with the face d^2 of the tension members A pulling against the face f of the key-piece, and the face d^3 of the tension member A' pulling against face f' of said key-piece, the key-piece, in this manner, counteracting the opposing forces to move the tension members longitudinally. Assuming, however, as the solder becomes melted or sufficiently softened so that it no longer can overcome the tendency of the members A and A' to separate, the forces for separating said tension members 55 are brought into operation with the result shown in Fig. 5. It will appear that the edge g of pocket d will be pulled upwardly by the force designated by the double arrows at the top of member A, 60 while the edge g' will be correspondingly pulled in the opposite direction. These forces will be transmitted to the key-piece B' as next to be described. The edge g' will press against the face f , as shown by 65 the arrow g^2 , and the edge g' will press

against the face f' , as shown by the arrow g^3 , and these forces, operating at the opposite sides of the center h of the key-piece B' , will impart a rotary movement to said key-piece about center h . It will be remembered, however, that the face e of the key-piece was in face abutting relation to the inner face of the tension member A while the face e' bore a corresponding relation to the inner face of tension member A' so that, 70 as soon as the key-piece commences to rotate, the edge i is pressed against the inner face of member A as shown by arrow i^2 , while the edge i' is pressed against the inner face of member A' as shown by arrow 80 i^3 . As a result of the co-action of these forces, which will be referred to by the arrows, it will be apparent that both of the forces g^2 and g^3 , serving to rotate the key-piece about its center h^2 , will set up 85 the forces i^2 and i^3 . It may thus be said that the operation of pulling the tension members apart longitudinally produces forces g^2 and g^3 to rotate the key-piece while these forces set up forces i^2 and i^3 which 90 serve to pry said tension members apart, *i. e.*, cause them to separate in a direction perpendicular to their adjacent faces.

In other words, they may be said to be a double bellcrank leverage arrangement, one 95 bellcrank being considered as extending from the edge g' to the center h and thence to the edge i' , while the other bellcrank theoretically extends from the edge g to the center h and thence to the edge i . The 100 work-arm of the first mentioned theoretical bellcrank may be said to be an imaginary line $g'h$ and the power-arm $h'i'$, while the work-arm of the other theoretical bellcrank is an imaginary line gh and the power-arm 105 hi . The work-arms of both these theoretical bellcranks impart rotary movement to the key-piece, while their power-arms pry apart the tension members. This operation continues from the very time that the solder 110 becomes soft enough to yield until the edges g and g' slip off of the faces f and f' , whereupon there is nothing to further restrain the opposite movement of the tension members A and A' , and they slip longitudinally 115 of one another and are entirely released.

The faces d^2 and d^3 are, in effect, abutments formed in the depressions or pockets of the tension members which are frequently 120 known in the trade as tension plates while the faces e and e' , f and f' constitute additional abutments on the key-piece. It will be apparent that the abutment d^2 co-operates with the abutment f of the key-piece, that the abutment d^3 co-operates with the abutment f' of the key-piece, that the abutment e co-operates with the inner face of the tension plate A, and that the abutment e' co- 125 operates with the inner face of tension plate 130

A'. The abutments d^2 and d^3 of the tension plates acting upon the abutments f and f' of the key-piece transmit rotary movement to the key-piece and cause the abutments e and 5 e' to operate upon the inner faces of the tension members to forcibly pry them apart.

The foregoing prying action of the key-piece in releasing the parts of the links is, so far as I am aware, distinctly novel and 10 produces very forcible opening or disruption of the parts. Moreover, the distance to which the tension members need to be forced apart is much less than has heretofore been the case with strut links, while the advantage 15 of the strut links in having flat faces cooperate with one another to produce great strength and withholding power as embodied in a link of this invention.

Throughout the foregoing description the 20 structure shown in Figs. 1, 3 and 6 has been described as the preferred form of the invention, and, in many cases, this form is preferred. However, the structure of the remaining figures of the drawings possess advantages 25 over the said preferred form, the most striking of which is the fact that the key-piece is entirely inclosed and corrosion cannot set in at the edges of the link as might be the case with the link of Fig. 1, if 30 said link were improperly soldered. In the structure of Fig. 2 the key-piece is entirely surrounded by solder and corrosion cannot possibly occur.

Having thus fully described the invention, 35 what I claim as new, and desire to secure by Letters Patent, is:

1. A fusible link embodying a pair of lapped tension plates, each of which is provided on its inner face with a depression or 40 pocket, tapering in a direction longitudinally of the plate to form, at the end of each pocket, an abutment extending transversely of the plate, said depressions or pockets collectively forming a chamber when the plates 45 are in lapped relation, a key-piece positioned in said chamber and provided with abutments engaging with the abutments of the depressions or pockets, and other abutments engaging with the inner faces of the plates, 50 fusible solder for uniting the parts, whereby, when the solder is melted, the abutments of the depressions act upon the key-piece abutments which they engage to force the other abutments of the key-piece against 55 the inner faces of the plates for the purpose of forcibly prying the plates apart.

2. A fusible link embodying a pair of lapped tension plates, each of which is provided with a transverse abutment, a key-

piece provided with abutments coöperating 60 with the abutments of the tension plates and with shoulders engaging with the inner faces of said plates, and fusible solder uniting the parts, whereby when said solder is melted, the abutments of the plates act 65 upon the abutments of the key-piece to rotate said key-piece and force the shoulders against the inner faces of the plates for the purpose of forcibly separating said plates.

3. A fusible link embodying a pair of 70 lapped tension plates, each of which is provided with a depression forming an abutment, said depressions collectively forming a chamber to house a key-piece when the plates are in lapped relation, a key-piece 75 housed in said chamber, and fusible solder for uniting the parts, the abutments of the tension plates coöperating with the key-piece relatively adjacent the transverse axis thereof to impart rotary movement thereto, 80 when the fusible solder is melted, and the key-piece also coöperating with the tension plates relatively distant from said transverse axis to pry the plates apart when the key-piece is rotated.

4. A fusible link embodying two complementary tension members, each of which is provided with a shoulder, a key-piece provided with shoulders coöperating with the shoulders of the tension members, and with 90 further shoulders engaging the adjacent faces of the tension members and fusible solder for uniting the parts, whereby when the solder is melted, the shoulders of the tension members impart rotary movement to 95 the key-piece, causing the shoulders of the key-piece which engage with the adjacent faces of the tension members, to force or pry said members apart.

5. A fusible link embodying a pair of 100 lapped tension plates each of which is provided with an abutment, a key-piece positioned between said plates, provided with abutments engaging with the abutments of the tension plates, and with additional abutments engaging with the adjacent faces of said plates, and fusible solder for uniting the parts, whereby when the solder is melted the abutments of the tension plates act 105 upon the coöperating abutments of the key-piece to impart rotary movement to said key-piece and thereby cause the other abutments of the key-piece to pry the tension plates apart.

In testimony whereof I have signed my 115 name to this specification.

JAMES H. McDOWELL.
